UNITED STATES PATENT OFFICE.

CHESTER M. MOORE, OF WAKEFIELD, MASSACHUSETTS, ASSIGNOR TO MOORE SHANK COMPANY, OF EVERETT, MASSACHUSETTS, A CORPORATION OF MASSACHUSETTS.

SHANK STIFFENER.

Application filed July 24, 1925. Serial No. 45,941.

This invention relates to shank stiffeners and aims to provide an improved stiffener having, among others, the advantages herein pointed out.

5 In the drawings of one embodiment of my invention described and illustrated herein,

Fig. 1 is a plan or top view;

Fig. 2, an edge view;

Fig. 3, a bottom view;

10 Fig. 4, a broken out longitudinal section on an enlarged scale on the line 4—4, Fig. 1;

Figs. 5, 6 and 7 respectively, plan, edge and bottom views of a stiffener of different shape;

15 Figs. 8, 9 and 10, plan, edge and bottom views respectively, of another form of stiffener;

Figs. 11, 12 and 13 respectively, plan, edge and bottom views of a modified form 20 of spur; and

Figs. 14, 15, 16 and 17 still further modified forms of spurs.

Referring first to Figs. 1, 2, 3 and 4, my 25 novel shank stiffener comprises preferably a narrow strip or body 1, of suitably tempered

material, as metal, drilled or punched at suitable points, herein two, 2, 3. A suitable

30 spur which is preferably an untempered tack 4 is inserted through the body 1 in the direction desired from the back or bottom face.

This spur is then secured in position in the body in any suitable manner, preferably by upsetting some of the metal of the shank of the spur against the upper face or top of

35 the body 1. There are several ways in which this can be done and the one that I prefer to use consists in driving the tack into a mold or die that is slightly too small for it, whereby some of the metal on the

40 side faces of the shank of the tack will be forced up toward the head of the tack and against the body 1, and into the hole 2 partly filling it with the tack shank and locking the latter tightly therein, see Figs. 1, 2, 3, 4,

45 so that the stiffeners may thereafter be handled and shipped freely with no danger of the tacks coming out. This type of stiffener is frequently used on insoles. If a tack with a round shank is used, the metal will usually

50 be upset all around it, but if a tack with an oval shank is used, the metal may be upset only part way around the shank. This construction is preferred to a construction where the holes 2—3 are drilled of a uniform size

55 somewhat smaller than the tack shank, and

then the latter thrust through the hole and friction is relied upon to hold the tack in position. The friction of the shoe shank stiffener upon the tack shank will vary according to the nature of the shank stiffener material and is not sufficiently uniform for good results. Even if the tack is held sufficiently firmly by friction, it is not at all certain that it will be held upright relative to the shank stiffener, but frequently it will be bent over or canted and must be straightened by hand before it can be driven into position in the shoe, entailing a loss of time. Furthermore, the friction will vary according to whether the tack shank is round or oval, both kinds being used, and such stiffener cannot be shipped and handled safely.

Or, if the tack is driven through a soft shank stiffener not drilled and the latter then tempered, it will also result in tempering the tack, which is not desired, and then the tack must have its temper drawn.

Again, my construction is an advantage over such a construction above pointed out where the tack is thrust through a previously drilled hole smaller than the tack shank, and some of the metal of the tack shank is thereby pushed up and against the shank stiffener because in the latter case the metal of the tack pushed up by the forcing of the tack through the hole in the tempered stiffener prevents the subsequent proper upsetting to the desired extent of the tack shank about and perhaps into the opening in the shank stiffener; and further, the shank stiffener metal surrounding the tack shank may

60 be bent out of its proper plane somewhat and will not permit the upset tack shank metal to be upset as firmly as it otherwise would be if the surrounding shank stiffener metal lay flat and smooth. In my construction the holes having been previously drilled of a size to take the extreme large size of tack, it

65 matters little whether the tack shank is round or oval, or whether it is of a uniform size, because the metal is upset over and upon the adjacent face of the shank stiffener and partly into the hole in the shoe shank to fill it sufficiently to position the tack upright therein and lock it without relying

70 upon the spring of the shoe shank metal to do it.

75 In Figs. 5, 6 and 7 is illustrated a different form of stiffener such as is used with a filler.

100

105

110

In Figs. 8, 9 and 10 is shown a different shaped stiffener used principally on insoles.

In Figs. 11, 12 and 13 is illustrated a different form of spur for such stiffeners, provided in this case with a collar 5 on the shank which, when the head 6 of the spur, at the lower end of the stiffener, is headed over as at the upper end, securely locks the tack to the body 1 on the front or upper face, some of the metal being crowded between the spur and opening wall.

Again in Figs. 14, 15 and 16, is shown a further modification of the spur construction wherein the point is inserted through an opening in the body 1, and then further headed over to lock it therein. The blow on the head 6 of the tack causes it to partly at least fill in the opening sufficiently tight to securely lock the tack to the body. In whatever manner the tacks may be locked into the body they provide a novel and superior construction.

In Fig. 17 is shown a construction comprising a double pointed tack, the shanks of which may be partly upset against the body 1 in the manner described.

In the use of shank stiffeners of this construction, the tacks will readily be driven straight because they are positioned upright relative to and in the body preferably by machine, while hand positioned tacks individually handled in the common manner are frequently improperly positioned and therefore driven crooked. My novel stiffeners may be more quickly applied than those with tacks loosely inserted, because so much time is lost picking up and positioning the separate tacks in the latter case. It has been shown that an operator can in the same length of time apply about three times as many of my novel shank stiffeners with the tacks or spurs thereon as he can of the common kind of stiffeners without spurs.

My novel shank being of tempered metal is of course better than an untempered one and the stiffener is thus a better support

for the arch of the foot. Such a stiffener is better than a body with soft metal spurs struck up from the body because the tacks are more slender and more easily driven, and therefore cut their way more cleanly into the filler or insole and clinch down tightly without forming any hump on the end.

Furthermore, my stiffener is better because the spur is the metal of the previously formed tack shank, and will not break or distort in shape as do metal spurs struck up from the stiffener body which break frequently when the metal is turned over and distorted to form the spurs or break later from bend strain. Also the spurs of previously fashioned metal are stronger, as all the grain of the metal of the spur shank is compressed and runs in the direction of travel of the spur.

My invention is not limited to the particular embodiment thereof described and illustrated herein.

Claims.

1. As an article of manufacture, a shoe shank stiffener with an aperture therethrough, and a pointed spur passed through the aperture and permanently secured in position therein by the spur shank swaged into holding engagement with the stiffener. 70

2. As an article of manufacture, a shoe shank stiffener with an aperture therethrough, and a pointed spur passed through the aperture and permanently secured in position therein by metal of the spur shank displaced and partly filling in the aperture about the spur. 80

3. As an article of manufacture, a shoe shank stiffener with an aperture therethrough, and a pointed spur passed through the aperture and permanently secured in position therein by displaced metal of the spur shank partly overlying the aperture. 85

In testimony whereof, I have signed my name to this specification.

CHESTER M. MOORE.
